Primary Examiner — Lauren D McVey(74) *Attorney, Agent, or Firm* — Hanley Flight & Zimmerman LLC(57) **CLAIM**

The ornamental design for “textile printer”, as shown and described.

DESCRIPTION

FIG. 1 is a left, front perspective view of a textile printer showing our new design;

FIG. 2 is a right, front perspective view of the textile printer of FIG. 1;

FIG. 3 is a front elevation view of the textile printer of FIG. 1;

FIG. 4 is an enlarged left side elevation view of the textile printer of FIG. 1;

FIG. 5 is an enlarged right side elevation view of the textile printer of FIG. 1; and,

FIG. 6 is a front elevation view of a textile printer of FIG. 1 with cross-hatching that denotes a color contrast.

The dashed broken lines show portions of the textile printer and surfaces adjacent the dashed broken lines that form no part of the claimed design.

The dotted broken lines that are immediately adjacent to the claimed areas and define broken line regions depict the bounds of the claimed design.

The broken lines form no part of the claimed design.

1 Claim, 6 Drawing Sheets(56)
